UNITED STATES PATENT OFFICE.

EDWARD J. MOSKOW, OF ST. LOUIS, MISSOURI.

SHOE LENGTHENER.

Application filed June 13, 1925. Serial No. 36,782.

This invention relates to an improvement in shoe lengtheners and has for its primary object the purpose of providing a foot portion having a movable heel portion which is adapted to be moved from the foot portion.

Another object of the invention is in providing the heel portion of the shoe lengthener with a rigidly secured threaded rod which is extended therefrom into the foot portion, the foot portion being provided with means which are effective on the rod towards moving the heel portion during the shoe stretching operation.

15 A further object of the invention is in providing the shoe lengthener with an improved form of guiding means for actuating the heel portion of the shoe lengthener.

Other and further objects will appear in 20 the specification and be specifically pointed out in the appended claims, reference being had to the accompanying drawings exemplifying the invention, and in which,

25 Figure 1 is a longitudinal vertical section taken through this improved shoe lengthener.

Figure 2 is a fragmentary transverse horizontal section taken approximately on the line II—II of Fig. 1.

30 Figure 3 is a transverse vertical section taken on the line III—III of Fig. 1.

Referring by numerals to the accompanying drawings 1 designates a foot portion having a toe portion 2, and a movable heel portion 3, and rigidly secured to and extended from the heel portion 3 are a pair of paralleling guide rods 4, each of said guide rods being disposed in a respective guideway 5, said guideways being horizontally 35 formed in the foot portion 1.

Formed in the foot portion 1, and disposed between the pair of guideways 5, is a pocket 6, and located in said pocket are a pair of meshing bevel gears 7 and 8, the hub 45 of the gear 7 being provided with an interiorly threaded bore 9, said gear 7 being mounted on a horizontally disposed threaded rod 10 which is extended from and rigidly secured to the heel portion 3, the threads of said gear 7 being in mesh with the threads of the rod 10.

The gear 8 is disposed above the rod 10 and is rigidly secured to the lower end of a vertically disposed shaft 11, the bearing 12

for said shaft being formed in the upper 55 wall 13 of the pocket 6 which is formed in the foot portion 1, said shaft at its upper end having a handle portion 14 secured thereto.

The toe portion 2 of the foot portion 1 60 is provided at its end with a recess 15, said recess being for the reception of pin 16 of a removable toe-tip 17, said toe-tip being one of several different shaped toe-tips which are applicable to a device of this character. 65

In the operation of this improved shoe lengthener, when the lengthener is being placed in the shoe, it is desirable to reduce the length thereof, in which the heel portion 3 will be drawn or moved towards the 70 foot portion 1 by manipulating the handle 14 and turning the shaft 11 in which the gears 7 and 8 will be operated and the interior threads of the gear 7 will become active on the spirally threaded rod 10, thereby drawing said rod inwardly and the heel portion 3 therewith. After the lengthener has been properly inserted, the shaft 11 is manipulated in a right-hand direction thereby operating the gears 7 and 8, and the gear 75 80 will become active on the rod 10 and force said rod and the heel portion 3 outwardly against the back of the shoe and in which the foot portion 1 and the shoe tip 17 will be forced forwardly in which the shoe tip 85 will firmly press against the toe material of the shoe, thereby stretching the length of the shoe.

In the moving operation of the heel portion 3, the guide rods 4 will properly guide 90 95 the heel portion.

For removing the shoe lengthener after a shoe stretching operation, it is obvious that it will be necessary to manipulate the shaft 11 in a left-hand direction so that the gears 7 and 8 will be operated and the gear 7 will become effective in drawing in the rod 10 and the heel portion 3 therewith.

For supporting the extending end of the rod 10 a guideway 18 is provided in the foot 100 portion 1.

What I claim is:—

1. A shoe lengthener comprising a foot portion, a heel portion supported from said foot portion, a threaded rod rigidly supported from said heel portion, a gear mounted on said rod having interiorly formed threads for engagement with the threads of

said rod, and means borne by said foot portion which are co-operable with said gear for actuating said gear.

2. A shoe lengthener comprising a foot portion, a heel portion supported from said foot portion, a threaded rod rigidly supported from said heel portion, a gear mount-

ed on said rod having interiorly formed threads for engagement with the threads of said rod, a second gear in mesh with said first mentioned gear, and an operating shaft borne by said foot portion secured to said second mentioned gear.

EDWARD J. MOSKOW.
